(57) **CLAIM**

The ornamental design for an adjustable cell phone holster, as shown and described.

DESCRIPTION

FIG. 1 is a top plan view of a first cell phone holster shoulder member that forms a portion of a first embodiment of the invention;

FIG. 2 is a rear view of the shoulder member of FIG. 1.

FIG. 3 is a side view of the shoulder member of FIG. 1;

FIG. 4 is a side view of the shoulder member of FIG. 1;

FIG. 5 is a top plan view of a second cell phone holster shoulder member having adjustment apertures, that forms a portion of the first embodiment of the invention;

FIG. 6 is a rear view of the shoulder member of FIG. 5.

FIG. 7 is a side view of the shoulder member of FIG. 5;

FIG. 8 is a side view of the shoulder member of FIG. 5;

FIG. 9 is a front view of an adjustable cell phone holster, shown in use and with non-claimed environment, in accordance with the first embodiment of the present invention; FIG. 10 is a rear view of the cell phone holster of FIG. 9, shown in use and with non-claimed environment.

FIG. 11 is a front view of a cell phone holster, shown in use, in accordance with a second embodiment of the present invention; and,

FIG. 12 is a front view of a cell phone holster, shown in use, in accordance with a third embodiment of the present invention.

The broken line showing is for illustrative purposes only and forms no part of the claimed design.
